UNITED STATES PATENT OFFICE.

HARRISON GASTON BREWER, OF WASHINGTON, DISTRICT OF COLUMBIA.

DESIGN FOR A BADGE.

SPECIFICATION forming part of Design No. 31,058, dated June 27, 1899.

Application filed May 22, 1899. Serial No. 717,856. Term of patent 3½ years.

To all whom it may concern:

Be it known that I, HARRISON GASTON BREWER, a citizen of the United States, residing at No. 2008 F street northwest, in the city of Washington, District of Columbia, have invented and produced a new and original Design for a Badge, of which this is a specification, reference being had to the accompanying drawing, forming part thereof.

- 10 The figure represents the design in plan. As shown in the drawing, the leading or material feature of my design consists of several figures upon a circular base, comprising the military design shown. The central 15 figure represents a portrait representing W. J. Bryan. The figure on the left represents the Republic holding the globe, surmounted by an eagle in her left hand and pointing

with the staff in her right hand to the United States. The figure on the right represents 20 Peace crowning Bryan. The rays of the sun are represented above the eagle. Under the central figure is a shield for suitable inscription.

It is apparent that this design is applicable 25 for many decorative purposes.

Having described my design, what I claim as new, and desire to secure by Letters Patent, is—

The design for a badge, substantially as 30 herein shown and described.

HARRISON GASTON BREWER.
